WILLIAM F. DAVISON, OLIVER A. BATES, SAMUEL M. WILSON, AND ALVA P. RUSSELL, OF JANEVILLE, WISCONSIN.

Letters Patent No. 72,482, dated December 24, 1867.

IMPROVED HARNESS-SNAP.

The Schedule referred to in these Letters Patent and making part of the same.

Be it known that we, WILLIAM F. DAVISON, OLIVER A. BATES, SAMUEL M. WILSON, and ALVA P. RUSSELL, of Janesville, in the county of Rock, in the State of Wisconsin, have invented a new and improved Snap and Check-Hook for Harnesses, and for other purposes; and we do hereby declare that the following is a full clear, and exact description thereof, reference being had to the accompanying drawings, and to the letters of reference marked thereon, the same letter of reference representing the same part in each drawing.

The nature of our invention consists in applying, inside the hook of a snap, a ring, pivoted to one side or arm of the hook, while a spring keeps the opposite side of the ring pressed against the opposite side of the hook, in a diagonal position across the space between the arms of the hook, whereby, when in use, it cannot, by accident or rubbing of a horse, become unhooked; and, also, the circular form of the ring, by its diameter, furnishes a convenient means of pressing the ring inward for unhooking, especially in cold weather, when gloves and mittens are worn, or in the dark, when the sense of feeling must govern in attaching and detaching the snap, and is applicable, not only for check-reins and lines, but also for whiffle-trees, and for other purposes for which snaps are used.

Figure 1 is a side view of the hook and ring-snap,

Figure 2 is a view at right angles with fig. 1, and

Figure 3 is a longitudinal section at right angles with fig. 1, and shows a part of the ring, hook, and spring.

a is the body of the hook, having the loop *d* at one end, to which the rein, trace, strap, &c., are attached, while at the other end is attached the ring *b*. At *f* the end of the bar composing the body of the hook is forked or formed with a mortise, to receive the spring *c* and allow it to operate freely, while the fork is bent so as to form an eye to receive the ring *b*, as shown in fig. 3. *e* is the rivet that holds one end of the spring *c* firmly to the body of the hook, while its opposite end is left free to rise and fall in the fork at *f*, before described.

When the ring is pressed inward, as the hook is used in attaching and detaching from the bit of the bridle, and when used for other purposes, the gain or flattened portion of the inside of the ring at *h* serves the double purpose of keeping the ring from rotating or revolving in a longitudinal direction, and, by the pressure of the spring thereon, keeps the ring pressed against the opposite side of the hook from that part to which it is fastened, as shown in fig. 1. Now, it is obvious, that as the ring *b* is pressed within the hook, in the direction of the dotted lines *b'*, the right-hand corner of the flattened part of the inside of the ring, as at *h* in fig. 3, will raise the spring *c*, and, the moment the pressure on the spring is removed, the spring forces the ring to its original position. This inward inclination of the ring is accomplished by the act of hooking upon a bridle-bit, or other article, when used, while, to unhook it, the pressure of the ring in an inward direction becomes necessary.

We do not confine ourselves to the precise mode described and shown for the construction of our ring-snap hook; but the ring, its flattened portion, or its equivalent shape, to operate against a spring, and the forked end of the hook, in some manner substantially as described, we deem essential in its construction; also its application and use is as broad as the purposes for which its snap-hooks are used.

Among the advantages of our ring-snap hook, we may enumerate that of reliability, the ring being as strong, substantially, as any part of the hook. It is not easily broken by the rubbing caused by the restlessness of horses, sudden concussion, or other accident. The location of the spring that operates the ring, being in a safe place, is less liable to damage, by breaking or otherwise, than when located in a more exposed position, or when it receives the pressure direct, as from a bridle-bit ring, instead of our intermediate ring *b*; and also the ring may be readily used in the dark, and in cold weather without removing mittens or gloves.

What we claim as our invention, and desire to secure by Letters Patent, is—

1. Ring *b*, when constructed with a gain or flattened portion to receive and to be operated by spring *c*, substantially as and for the purposes described.
2. Hook *a*, ring *b*, and spring *c*, when all are constructed, connected together, and used substantially as and for the purposes described.

WILLIAM F. DAVISON,
OLIVER A. BATES,
SAMUEL M. WILSON,
ALVA P. RUSSELL.
